UNITED STATES PATENT OFFICE.

JAMES A. HINSON, OF CHICAGO, ILLINOIS.

DRAFT-RIGGING FOR RAILWAY-CAR COUPLINGS.

SPECIFICATION forming part of Letters Patent No. 709,404, dated September 16, 1902.

Application filed December 28, 1901. Serial No. 87,554. (No model.)

To all whom it may concern:

Be it known that I, JAMES A. HINSON, of Chicago, in the county of Cook and State of Illinois, have invented certain new and useful Improvements in Draft-Rigging for Railway-Car Couplers; and I do hereby declare that the following is a full, clear, and exact description thereof, reference being had to the accompanying drawings, and to the letters of reference marked thereon, which form a part of this specification.

This invention relates to improvements in draw-bar draft-rigging for railway-cars, of that class in which a cumulative resistance is employed to absorb the shock of sudden impact and of recoil of the parts under the action of the springs occurring during the operations of coupling and in tractive uses.

The invention consists in the matters hereinafter set forth, and more particularly pointed out in the appended claims.

As shown in the drawings, Figure 1 is a longitudinal section of a draft-rigging embodying my improvements, taken on line 1 1 25 of Fig. 2. Fig. 2 is a plan view thereof with parts broken away and with the draft-sills shown in horizontal section. Fig. 3 is a transverse vertical section taken on line 3 3 of Fig. 1. Fig. 4 is a plan view, partly in section, 30 of a draft-rigging, showing a modification of my improvements. Fig. 5 is a longitudinal sectional view thereof, with parts shown in elevation and other parts broken away. Fig. 6 is a transverse vertical section on line 6 6 35 of Fig. 5. Fig. 7 is a side elevation of one of the bearing-blocks for the draw-bar spring removed from the other parts of the mechanism.

As shown in the drawings, A A designate 40 the draft-sills, which are secured to the lower surface of longitudinal floor-sills B by rivets b or other suitable means. C designates the draw-bar of the coupler, which is located centrally between the said draft-sills. D designates a cast-metal tailpiece or yoke, which 45 is secured to and projects rearwardly from said draw-bar, said tailpiece being for this purpose provided with forwardly-projecting flanges d, which embrace and are riveted to 50 an enlargement or head c at the rear end of the draw-bar. Said draft-sills and the car-

sills are shown as made of flanged metal bars, the webs of the draft-sills being reinforced by flat plates or bars riveted thereto; but it will be understood that my improvements 55 may be applied to wood car constructions or combined metal and wood constructions.

The tailpiece is provided near its forward and rearward extremities with two horizontal transverse elongated slots or openings d' d', 60 through which extend two horizontally-disposed follower-bars E E. Said bars are supported at their intermediate portions by said tailpiece and extend at their ends through openings a in the draft-sills corresponding in 65 size and aligned with the openings d' of the tailpiece, said bars extending a distance beyond said draft-sills A. The length of said slots a and d' exceeds the width of said follower-bars E, thereby affording relative movement of the 70 bars to the tailpiece and to the draft-sills. Two sets of inner and outer coiled expansively-acting springs F F' are interposed between the ends of said follower-bars E outside of the draft-sills and are supported thereon by horizontal retaining-bars F², which extend through 75 said springs and extend between and are connected at their ends with said follower-bars. As herein shown, the ends of said retaining-bars overlie the follower-bars and are folded 80 at their ends down over the edges of the follower-bars, as shown by dotted lines in Fig. 3. Keys f, extending through the follower-bars outside of the retaining-bars, prevent the 85 same and the springs shifting outwardly, and the draft-sills prevent inward shifting of the springs.

Coöperating with the springs F F' are supplemental resistance elements consisting of 90 combined roller and friction devices which operate to produce a cumulative resistance to the movement of the draw-bar when brought into action and also act to absorb a portion of the recoil of the parts under the action of the springs placed under tension. Said supplemental resistance elements or devices as 95 shown in the present construction consist of movable and stationary coacting friction-surfaces on one side of the tailpiece or yoke of the draw-bar and coacting inclined surfaces 100 and a roller on the other side of the tailpiece, one carried by the draft-sills and the other

by the tailpiece, said parts being maintained in proper coacting relation by spring-pressure.

As herein shown, G designates a horizontally-disposed block, which is pivotally supported upon a transverse bar or girder H, extending between and attached at its ends to the draft-sills in the manner shown in Fig. 3. The pivotal connection of said block with the bar consists of a downwardly-facing transverse groove on the under side of the block, which engages or fits over a raised transverse rib H' on the bar.

G' designates an upwardly-facing friction-plate on the block G, which engages a downwardly-facing friction-plate D' on the under side of the tailpiece. The friction-plates G' and D' are held from longitudinal and lateral displacement on the block and tailpiece by means of lugs d³ g on the tailpiece and block, which extend through openings in said plates D' and G', respectively, said lugs being flush at their ends with the bearing-surfaces of said plates.

25 The pivotal connection of the block G with the transverse bar or girder H enables the friction-plates carried by said block and the tailpiece to be maintained in parallelism notwithstanding wear on said parts.

30 Desirably the draft-sills and the associated parts are braced from distortion by means of brace-bars H², which extend laterally and obliquely upwardly from the lower margins of the sills to and are connected with intermediate longitudinal floor-sills B', as shown in Fig. 3, the inner ends of said brace-bars being clamped between the lower flanges of the draft-sills and the ends of the transverse bar or girder H, as shown in Fig. 3. Located centrally between said draft-sills and above the tailpiece is a rigid lever I, made, preferably, of cast metal. Said lever is pivoted between its ends upon a bolt I', which extends between and transversely through the webs of the draft-sills A, and the lever extends at its forward end over the rear end of the tail D of the draw-bar. Said lever I is provided between its ends with a massive hub i, through which said pivot-bolt extends, and the ends of said hub bear against the inner faces of the draft-sills, thereby retaining said lever in a central position with respect to the draft-sills. The lever is strengthened by a longitudinal centrally-located stiffening rib or ribs i' on the upper side thereof, extending throughout the principal part of the length of the lever. The lever is formed at its forward end to provide a downwardly-opening concave recess shaped to receive the body of a roller J and to form bearings for the trunnions of said roller. Said roller occupies an upwardly-facing recess formed in the top of the tailpiece between oppositely-inclined surfaces d³ d⁴. Said inclined bearing surfaces at their lowest parts are connected by a curved depression, which is occupied by the roller J when the draw-bar is at a central or rest position. The ra-

dius of the curve forming the bottom of said recess is somewhat greater than the roller, whereby the initial movement of the tailpiece in either direction will produce little or no effect on the lever. Spring-pressure is applied to the rear or tail end of the lever in a manner tending to hold the roller J pressed against the inclined surfaces d³ d⁴, whereby movement of the draw-bar and tailpiece is resisted by said spring. As herein shown, K K' designate outer and inner spiral springs, which are interposed between the tail end of the lever and a transverse bar or girder L, extending between and attached to the draft-sills, as by transverse bolts l. Said springs are held in place by means of inwardly-extending studs on the lever and bar, as indicated in dotted lines in Fig. 1.

85 A brief explanation of the action of the parts described in the foregoing may be stated as follows: The stress brought on the draw-bar when two cars are coupled together or when the train is suddenly stopped or started imposes to said draw-bar a movement the direction of which depends upon the direction of movement of the cars. Such movement of the draw-bar acts to compress the springs F F'. After an initial compression of said springs 90 one of the inclined surfaces d³ d⁴, depending upon the direction of movement of the draw-bar, acts on the roller J to throw or thrust the forward end of the lever I outwardly and the rear end thereof inwardly against the action of the springs K K'. The pressure exerted by the spring-pressed lever against the upper side of the tailpiece of the draw-bar is transmitted through said tailpiece to the friction-plates D' G', and resistance due to the friction between said plates is added to the spring resistance. Said combined spring and friction resistance is cumulative, being gradually increased as the draw-bar approaches the limit of its movement. Owing to the peculiar formation of the recess in the upper side of the tailpiece engaged by the roller J the springs K K' and the friction-producing means are not brought into action until the springs F F' have been placed under preliminary compression. These parts may be so proportioned that the springs K K' will not be brought into action during the slight movements of the draw-bar in ordinary tractive usage, such strains being only transmitted to the main draw-bar springs F F'. In the heavier strains, such as occur in coupling or in suddenly stopping and starting the train, the springs K K' and friction-producing means are brought into action, and the combined spring and friction resistance is such as to absorb the maximum practical strains brought upon the draft-rigging. The space occupied by the springs K K' is such that the strength or number of the lever-actuating springs may be increased at will, thereby enabling the strength of the rigging to be varied to correspond with any practical demands made thereon. The friction between the plates G² D² obviously

acts to retard the restoration of the parts to their central positions of rest, whereby the recoil of the parts is largely absorbed and the racking of the parts due to such recoil greatly diminished.

As shown in Figs. 5, 6, and 7, the draw-bar C is hinged to the tailpiece D in a manner to swing or oscillate in a horizontal plane. For this purpose the forward end of the tailpiece 10 of the draw-bar is provided, in lieu of the flanges d, (shown in the former figures,) with upwardly and downwardly extending trunnions d⁵ d⁶, which extend through openings in upper and lower plates C², projecting rearwardly from the head of said draw-bar. Keys 15 d⁶ are inserted through openings in the outer ends of the said lugs or trunnions outside the plates C² to hold the parts in their proper relative positions. The plates C² are riveted to 20 the head of the draw-bar in the manner shown in Fig. 5, and desirably the forward-most rivet passes through upper and lower narrow plates C³, located between the forward ends of said plates C² and the draw-bar 25 and engaging forwardly-facing shoulders on the draw-bar, as shown in Fig. 5. The front end of the tailpiece is curved, as indicated at b⁷, on an arc concentric with the axis of oscillation of said tailpiece, and the rear or adjacent end of said tailpiece is correspondingly 30 curved, whereby rolling contact is preserved between said parts in the swinging movement of said tailpiece. In this construction the retaining-bars F², by which the side springs F¹ are held in place, are omitted, and in lieu of such construction the following devices are provided for retaining said springs in place: The said springs bear at their ends against inwardly-facing vertically-disposed bearing- 35 plates M, attached to or formed on cast-metal loops M', which are adapted to be slipped over the ends of the follower-bars E in the manner shown in Fig. 4. Said loops are held in place on said follower-bars by means of bolts 40 m, passing downwardly therethrough and through said follower-bars. The bearing-plates are provided centrally thereof with lugs m', which pass into the innermost or smaller springs and serve to hold said springs 45 centrally. In the construction shown in the latter figures also the pivotal connection of the friction-blocks G with the supporting-bar or girder H is the reverse of that shown in Fig. 1—that is to say, the block G (shown in Fig. 5) is provided with a depending central rounded rib H², which fits within an upwardly-opening like-shaped transverse groove in the bar or girder H. The mechanical effect of this latter construction is obviously 50 the same as that before described.

In lieu of the spiral expansively-acting springs K K' interposed between the lever I and the cross-bar or girder L, I have shown in the latter modification the adaptation of leaf-springs to said lever.

The modified construction is shown more clearly in Figs. 4 and 5 and is made as fol-

lows: N N designate superimposed leaf-springs which are curved upwardly at their central portions and are supported on the upper face of the cross-bar or girder L. Said cross-bar or girder is provided at its side margins and near the ends thereof with a plurality of upwardly-directed flanges or lugs l', which constitute, in effect, an upwardly-opening box to receive the springs N. O designates a bearing-block which is interposed between said leaf-springs and the tail end of the lever. Said block is provided at its lower end with a wide flat face having marginal flanges o, adapted to overlap the margins of the springs, and is provided at its upper ends with a recess or socket which receives a centering-stud i³, depending from the tailpiece of said lever I. In lieu of the block O it may be desirable in some instances to interpose between the leaf-springs and the tail of the lever a spiral spring adapted to be compressed preliminary to the compression of the leaf-springs. In other respects the construction shown in Figs. 4 to 7, inclusive, is substantially the same as that shown in the figures first described.

It will be obvious that other changes than shown or indicated may be made without departing from the spirit of my invention and I do not wish to be limited to such details except as hereinafter made the subject of specific claims. For instance, I may employ the combined spring and friction resistance shown with the ordinary type of draw-bar draft-rigging, wherein the draw-bar spring is located within a yoke extending rearwardly from the draw-bar. The terms "tailpiece" and "yoke" used in the claims are therefore understood to designate either of the said constructions. Furthermore, the device may be applied to the two center-sills of a car where no subsills or draft-sills are employed.

I claim as my invention—

1. A draft-rigging for cars comprising a draw-bar, a draw-bar spring or springs and supplemental resistance elements coöperating with said draw-bar spring or springs comprising coacting friction-surfaces at one side of the draw-bar, coacting inclined surfaces and a roller at the other side of said bar, and a spring for holding said roller and inclined surfaces in coacting relation.

2. A draft-rigging for cars comprising a draw-bar, a draw-bar spring or springs and supplemental resistance elements coöperating with said draw-bar spring or springs comprising coacting friction-surfaces at one side of the draw-bar, coacting inclined surfaces and a roller at the other side of said bar, and a spring for holding said roller and inclined surfaces in coacting relation, the pressure of said springs being exerted through the draw-bar yoke or tailpiece to said friction-surfaces to hold the same pressed one against the other.

3. A draft-rigging for cars comprising a draw-bar, a draw-bar spring or springs which

are compressed through longitudinal movement of the draw-bar and supplemental resistance elements coöperating with said draw-bar spring or springs comprising coacting 5 friction-surfaces at one side of the draw-bar, coacting oppositely-inclined surfaces, and a roller at the other side of said bar, and a spring for holding said roller and inclined surfaces in coacting relation, said inclined 10 surfaces being connected by a curved surface formed on a greater radius than that of the roller, whereby the draw-bar spring or springs may be placed under preliminary compression prior to the operation of the supplemental 15 resistance elements.

4. A draft-rigging for cars comprising a draw-bar provided with a tailpiece or yoke, a draw-bar spring or springs, a friction-plate on one side of said tailpiece or yoke, a coacting 20 stationary friction-plate, a spring-pressed part at the other side of said draw-bar, and coacting parts on said spring-pressed part and the side of the draw-bar tailpiece or yoke remote from the friction-plates, comprising a 25 roller on one of said parts and oppositely-inclined surfaces on the other part.

5. A draft-rigging for cars comprising draft-sills, a draw-bar provided with a tailpiece or yoke, a draw-bar spring or springs, a flat friction-plate on one side of said draw-bar tailpiece or yoke, a friction-plate stationary with 30 the draft-sills and coacting with the movable friction-plate, a laterally-movable part supported on said draft-sills at the opposite side 35 of the draw-bar, coacting parts on said part and the draw-bar tailpiece or yoke, embracing inclined surfaces on one of said parts and a spring supported on said draft-sills acting to maintain said coacting parts in operative 40 relation.

6. A draft-rigging for cars comprising a draw-bar provided with a tailpiece or yoke, a draw-bar spring or springs, a friction-plate on one side of said draw-bar tailpiece or yoke, a coacting 45 stationary friction-plate, a spring-pressed part at the other side of said draw-bar, and coacting parts on said spring-pressed part and the adjacent side of the draw-bar tailpiece or yoke, comprising a roller on one 50 of said parts and oppositely-inclined surfaces on the other part, said stationary friction-plate having a limited oscillatory movement to maintain the friction-surfaces of the plates in parallelism.

55 7. A draft-rigging for cars comprising draft-sills, a draw-bar provided with a tailpiece or yoke, a draw-bar spring or springs, a friction-plate at one side of said draw-bar tailpiece or yoke, a stationary friction-plate supported on 60 said draft-sills and coöperating with the movable friction-plate, a vertically-oscillatory lever supported between said draft-sills, a roller carried by said lever, oppositely-inclined surfaces on the draw-bar tailpiece or yoke coacting 65 with said roller, and a spring supported on said draft-sills and acting on said lever to

press said roller against said inclined surfaces of the draw-bar.

8. A draft-rigging for cars comprising draft-sills, a draw-bar provided with a tailpiece or 70 yoke, a draw-bar spring or springs, a friction-plate at one side of said tailpiece or yoke, a stationary friction-plate supported on said draft-sills and coöperating with the movable friction-plate, a spring-pressed part supported 75 between said draft-sills and a roller carried by said spring-pressed part, oppositely-inclined surfaces on the draw-bar coacting with said roller, said inclined surfaces of the draw-bar being connected by a curved surface formed 80 on a radius greater than that of the roller.

9. A draft-rigging for cars, comprising draft-sills, a draw-bar provided with a yoke or tailpiece, a draw-bar spring or springs, a friction-plate at one side of the yoke or tail-piece, a friction-plate supported on said draft-sills and coöperating with the movable friction-plate, a spring-pressed part supported 85 by the draft-sills, coacting parts on said spring-pressed part and the side of the yoke 90 or tailpiece remote from the friction-plates embracing a roller on one of said parts, and inclined surfaces on the other part, one of said friction-plates having a limited or oscillatory movement with respect to its support 95 whereby said plates may be maintained in parallelism.

10. A draft-rigging for cars comprising draft-sills, a draw-bar provided with a tailpiece or yoke, a draw-bar spring or springs, 100 a friction-plate at one side of said tailpiece or yoke, a friction-plate supported on said draft-sills and coöperating with the movable friction-plate, an oscillatory lever supported between said draft-sills, a roller carried by 105 said lever, oppositely-inclined surfaces on the tailpiece or yoke coacting with said roller, and a spring supported on said draft-sills and acting on said lever to press said roller against said inclined surfaces of the draw-bar, said 110 stationary friction-plate having a limited oscillatory movement whereby said friction-plates may be maintained in parallelism.

11. A draft-rigging for cars comprising draft-sills, a draw-bar provided with a yoke 115 or tailpiece, a draw-bar spring or springs, a friction-plate on one side of said yoke or tailpiece, a bar or girder extending transversely between the draft-sills below said friction-plate, a second friction-plate carried by said 120 bar or girder and coacting with the draw-bar friction-plate, said second friction-plate having a limited oscillatory movement on said bar, and coacting inclined surfaces and a spring-pressed roller at the other side of said 125 yoke or tailpiece.

12. A draft-rigging for cars comprising a draw-bar, provided with a tailpiece or yoke to which the draw-bar is pivoted in a manner to swing horizontally, a draw-bar spring or 130 springs, a friction-plate at one side of said tailpiece or yoke, a stationary friction-plate

coacting with said tailpiece friction-plate, a spring-pressed part on the other side of said tailpiece, and coacting parts on the said spring-pressed part and the tailpiece, embracing oppositely-inclined surfaces on one of said parts, and a roller on the other part.

13. A draft - rigging for cars comprising draft-sills, a draw-bar, a tailpiece or yoke extending rearwardly from said car, follower-bars extending through openings in said tailpiece or yoke and through alined openings in the draft - sills, springs interposed between said follower-bars laterally outside of said draft-sills, a friction-plate at one side of said tailpiece or yoke, a coacting stationary friction-plate carried by the draft-sills, and coacting inclined surfaces and a spring-pressed roller on the other side of said tailpiece or yoke.

14. A draft - rigging for cars comprising draft-sills, a draw-bar, a tailpiece or yoke extending rearwardly therefrom, follower-bars extending through openings in said tailpiece or yoke and through alined openings in the draft-sills, springs interposed between said follower-bars laterally outside of said draft-sills, friction-plates on one side of said tailpiece or yoke, a friction-plate carried by the draft-sills, and coöperating with said friction-plate of the tailpiece or yoke, an oscillatory lever supported on said draft-sills, on the side of the tailpiece or yoke opposite to said friction-plates, a roller on said lever, inclined surfaces on the tailpiece or yoke coacting with said roller, and a spring supported on said draft-sills and acting through said lever to hold said roller in operative relation with respect to said inclined surfaces.

15. A draft - rigging for cars comprising draft-sills, a draw-bar, a tailpiece or yoke ex-

tending rearwardly from said draw-bar to which said draw-bar is pivoted in a manner to swing horizontally, follower-bars extending through openings in said tailpiece or yoke and through alined openings in the draft-sills, and springs interposed between said follower-bars laterally outside of said draft-sills. 45

16. A draft - rigging for cars comprising draft-sills, a draw-bar, a tailpiece or yoke extending rearwardly from said draw-bar, said tailpiece or yoke being provided on its forward end with oppositely-extending lugs, plates extending rearwardly from the upper and lower sides of the draw-bar and provided with openings through which said lugs extend, follower-bars extending through openings in said tailpiece or yoke and through alined openings in the draft-sills, and springs interposed between said follower-bars laterally outside of said draft-sills. 50

17. A draft - rigging for cars comprising draft-sills, a draw-bar, provided with a tailpiece or yoke, follower-bars extending transversely through openings in said tailpiece or yoke and through alined openings in the draft-sills, springs interposed between said follower-bars laterally outside of said draft-sills, and bearing-plates against which the ends of said springs bear, said plates being formed on or attached to loops which embrace said follower-bars and are attached thereto. 55

In testimony that I claim the foregoing as my invention I affix my signature, in presence of two witnesses, this 21st day of November, A. D. 1901.

JAMES A. HINSON.
